UNITED STATES PATENT OFFICE

CHARLES N. FAIRCHILD, OF PLANTSVILLE, CONNECTICUT, ASSIGNOR TO FAIRCHILD
LOCK CORPORATION, OF NEW YORK, N. Y., A CORPORATION OF DELAWARE

AUTOMOBILE LOCK

Application filed May 23, 1928. Serial No. 279,978.

This invention relates to automobile locks and has for one of its objects the provision of a lock which controls the ignition and which permits of variation of this control while its locking status remains unchanged.

A further and important object is to provide a novel arrangement of parts whereby it will be impossible for the ignition to be cut off simultaneously with the locking of the car accidentally or by inadvertence and whereby it will be impossible to lock or unlock the car without the use of both hands of the driver.

The arrangement in my device is such that in order to lock the car both hands must be used an act which cannot occur inadvertently or by accident while driving, but requires a deliberate and premeditated coincidence of separate acts.

The present invention coincides in the above objects with my co-pending application, Serial No. 255,440, filed February 18, 1928, but differs therefrom in the provision of different mechanism by which the objects are accomplished.

The present invention contemplates the provision of a locking bolt with means associated therewith for completing or breaking the ignition circuit at will, and key operated means for moving the bolt to and from locking position. It further contemplates the control of the ignition switch either simultaneously with or independently of the operation of the bolt. The above structure coincides substantially with that of the co-pending application mentioned above but in place of the rock shaft and lever of that device for preventing accidental locking of the car I provide in the present embodiment a push pin which is so located as normally to prevent the key actuated means from operating the bolt by obstructing the turning of the key at key entry position. The obstructing functioning of the pin is relieved by the pushing

of the pin against the force of a helical spring arranged in a suitable housing and surrounding the pin where the pin is in its normal position. The key is free to turn throughout the major portion of a complete rotation but is prevented from making the

last part of the revolution, i. e. that necessary to move the bolt from running position to locking position. To eliminate the hazard of accidentally moving the bolt to locking position I provide a latch which is normally held by a helical spring in the path of a collar formed on the push pin and which prevents operation of the push pin except by the use of both hands.

In the drawings:—

Figure 1 is an elevation.

Figure 2 is a plan view.

Figure 3 is a fragmentary detail view showing the casing in section and illustrating the relation of the push pins to each other.

Figure 4 is a section showing the bolt and ignition moving cam and the bolt pin in elevation.

Figure 5 is a vertical section thru the axis of the locking bolt.

Figure 6 is a horizontal section thru the axis of the push pin.

Figure 7 is a section thru the axis of the latch, the plane being at 45° to vertical and horizontal.

Referring now to the details of the mechanism by reference numerals, 10 designates the lock housing, 11 denotes the lock cylinder which may be turned by the key 12, and 13 denotes a cam secured to the rotatable cylinder and adapted to cooperate with a pin 14 secured to the locking bolt 15 for operating the latter. The ignition circuit control switch member includes a vertically slid able stem 17 having a follower 18 attached thereto which is provided with a depending finger 19 projecting normally across the path of rotation of the cam 13 and adapted to be raised thereby to force the switch member upwardly to complete the ignition circuit by contacting with the terminals 20 of the conductors of said circuit. Both the stem 17 and the bolt 15 tend to assume their lowermost positions under the influence of helical springs represented respectively 21 and 22 and are raised by the cam as described above.

All of the structure hereinbefore detailed is substantially in common with my above named co-pending application and I will now proceed to detail the structure varying

therefrom. Suitably located within the housing 10 I provide a bore 23 in which is slidably mounted the push pin or rod 24. This push rod is held normally in retracted position by means of a helical spring 25 abutting at its opposite ends against the shoulders 26 and 27 provided respectively integral with the housing and with the pin, the latter shoulder being provided by the formation on the pin of an annular ridge or collar 28.

10 The bore 23 communicates at its inner end with the slideway of the bolt 15 through an aperture 29 which is of sufficient diameter to permit the end 30 of the push rod 24 to project therethrough into one or the other of the 15 notches 31 or 32 formed in the bolt 15. The end 30 of the pin is reduced in diameter and tapered to its tip from a point a short distance from the tip and is provided with a shoulder 33 as a line of demarkation between 20 the cylindrical portion and the tapered portion of the pin.

The opposite end of the pin is provided with a head 34, affording a hand grip for use 25 in manipulation of the pin as will hereinafter be set forth. The head 34 is provided with a central knob or umbo 35 which normally lies in the path of rotation of a lug 36 formed on the head 37 of the key 12, the key and knob 30 being so related that the knob will prevent the key from turning thru the phase of its rotation effective in locking the car while at the same time permitting the key to freely turn thru the phase effective in manipulation 35 of the ignition circuit.

35 In order that the key may be turned thru the effective locking phase the push rod 24 must be forced inwardly against the resistance of its spring 25 and manually held in 40 such inner position for a portion of the time at least while the key is being turned. Thus it is seen that accidental turning of the key is rendered fairly impossible as it requires either wonderful dexterity or the use of both 45 of the driver's hands to accomplish the locking or unlocking of the car. However, to eliminate entirely all hazard, I provide an obstruction 38 on the inner headed end of a latch stem 39, the head of the latch being designated by the numeral 40. The head 40 also 50 serves to provide a shoulder 41 affording an abutment for one end of a helical spring 42 the opposite end of which abuts against a flange 43 of casing 44 fast to the casing 10 and having a bore 45 communicating at its 55 inner end with the bore 23 in which pin 24 moves. The spring 42 normally holds the latch end 38 in the path of the shoulder 27 so that it is necessary to withdraw the latch by 60 an outward pull on the latch against the influence of this spring.

To facilitate this movement the pin 39 is provided with a knob 46. The head 40 is of a size to have a snug sliding fit in the bore 65 45 and the stem of pin 39 has a snug sliding

fit thru an aperture 47 in the wall of the casting 44.

It will appear from the above that before the push rod 24 can be pushed inwardly the knob 46 and the head 34 must be seized with the two hands and the collar 28 must be 70 pushed beyond the path of latch while the latter is withdrawn from the path of travel of the rod. Rod 24 is now free to move to clear the key.

The operation of the above described mechanism is as follows, the parts being in position as represented in the drawings, that is, in car locking position. Presuming that it is desired to unlock the car and start the ignition, the latch 39 is drawn outwardly 75 freeing the path of collar 28 of obstruction, and push rod 24 is pushed inwardly, the key 12 is now turned until the push rod is free to snap back. The key is now turned further for the locking bolt is no longer held by the push rod so the cam 13 contacts with finger 19 and the locking bolt pin 14 so that further turning will raise the member 17 causing the bridging of the gap between contacts 20 and will unlock the car. 80 90

With the parts in unlocked or running position the key is free to turn the ignition on or off as desired by the driver but is held in the locking cylinder so that it cannot be withdrawn, once the parts have been moved to running position, except by using both hands to turn the key to withdrawing position. The key cannot make a complete revolution because it would engage the push rod. The push rod, however, can be pushed inwardly if the latch is pulled out to permit this movement. Such an act requires the use of both hands and obviously both hands can never be free inadvertently while driving for the car would be out of control the moment both hands are taken from the steering wheel. It is obvious, therefore, that the key can be turned to key removing position only when the car is still so that both hands are free to manipulate the necessary elements as outlined. When the push rod has been depressed the key can be moved to the so-called 360° position which is a complete revolution from entry position and at this time the spring 25 is free to move the push rod to its normal position moving the key with it. 100 105 110 115

I rather prefer to have a small lug 49 integral with the key so that in case of any accident the pulling out of the key would pull the push rod out which would permit the making of the spring 25 considerably lighter. It is proposed, however, to make the spring fairly heavy so that it can eject the key. It will be understood that the latch affords no 120 obstruction whatsoever to the outward movement of the push rod and also that in its inward position after the car has been running the push rod itself holds the bolt up by its engagement with the smaller notch 32 which 125 130

permits only very slight movement of the bolt when the push rod is in active position, whereas the large notch 31 necessarily permits a rather considerable movement of the bolt under the action of the locking cylinder 5 cam while the push rod is in depressed position.

What I claim is:—

1. In a device of the character described, a bolt, a key operated mechanism for manipulating said bolt, means lying normally in the path of rotation of the key but movable out of the path of the key, and means positively holding the first named means in key obstructing position, but manually movable to permit movement of the first means out of the path of the key.

2. In a device of the character described, a bolt for locking a vehicle against operation, means operable by a key for manipulating the bolt, means normally held yieldably in the path of rotation of the key and in such relation thereto as to prevent its rotation thru its bolt manipulating phase when in normal position.

3. In combination with a locking bolt, means for moving the bolt to unlocking position and a push pin normally in position to obstruct the operation of the bolt for the above purpose, said push pin being so devised that it may be manually released from obstructing position, and means for automatically returning the push pin to obstructing position when released.

4. In combination with a key operated locking bolt, means for moving said bolt to locking position, and means for preventing accidental and inadvertent movement of said bolt, including key obstructing means movable from obstructing position, said means so related that they must be simultaneously and separately operated to effect locking movement of the bolt.

5. In combination with a bolt, key operated means for moving said bolt, a push pin having a knob normally in obstructive relation to the key for preventing the movement of the bolt thereby, said push pin being yieldably held in obstructing position.

6. In combination with a bolt, key operated means for moving said bolt, a push pin having a knob normally in obstructive relation to the key for preventing the movement of the bolt thereby, said push pin being yieldably held in obstructing position, and a latch normally preventing the movement of said push pin from obstructing position.

7. In combination with a locking bolt, key operated means for moving said bolt to locking position, and means for preventing accidental and inadvertent movement of said bolt, including key obstructing means movable from obstructing position, said means so related that they must be simultaneously and separately operated to effect locking move-

ment of the bolt, and means for normally preventing the movement of said obstructing means, removable at will from its movement preventing position.

8. In combination with a steering post lock having a bolt, key operated means for moving said bolt, and means insuring against accidental movement of said operating means to effect the movement of the bolt consisting in a pair of co-related push pins, one of which serves to yieldably obstruct the operation of the key and the other serving to latch the first against accidental operation.

9. In combination with a steering post lock having a bolt, key operated means for moving said bolt, and means insuring against accidental movement of said operating means to effect the movement of the bolt consisting in a pair of co-related push pins, one of which serves to yieldably obstruct the operation of the key and the other serving to latch the first against accidental operation, said push pins being so related and constructed as to require simultaneous and separate operation to permit movement of the bolt to steering post locking position.

10. In combination, a bolt, key operated revolving means for moving the bolt, and a member lying in the path of rotation of the key but movable parallel to the axis of the means to free the key.

11. In combination, a bolt, key operated revolving means for moving the bolt, and a member lying in the path of rotation of the key but movable parallel to the axis of the means to free the key, and means normally holding the member against movement but movable to free the member so it may be moved out of the path of the bolt.

12. In a lock, a spring pressed bolt, key operated means for moving the bolt against the spring, and a member adapted to move to hold the bolt in unlocked position while the key is rotated to key removing position, and a spring to remove the member from bolt holding position and simultaneously to eject the key.

13. In a lock, a bolt, a key operated revolving cylinder lock for moving the bolt, a member for holding the bolt in unlocked position, and means to prevent independent sliding movement of the key and member when the key is in key withdrawing position.

14. In a lock, a bolt, having a groove therein at right angles to its axis, a member slideable into the groove to hold the bolt in unlocked position, means including a key operated revolving cylinder lock adapted to move thru a small angle while said member is holding the bolt in unlocked position, and means for ejecting the key at the end of said small angular movement of the key, said key ejecting means also releasing said member

from its locking engagement with the bolt.

15. In combination with a key operated lock, a push rod slidably in relation to the lock, adapted to prevent operation of the key when the push rod is in operative position.

70. In testimony whereof I affix my signature.

CHARLES N. FAIRCHILD.
